CLAIM

The ornamental design for a seal for flow control valve, as shown and described.

DESCRIPTION

Fig. 1 is a top, perspective view of a seal for flow control valve according to the present invention;

Fig. 2 is a top view of the seal for flow control valve shown in Fig. 1;

Fig. 3 is a bottom view of the seal for flow control valve shown in Fig. 1;

Fig. 4 is a front view of the seal for flow control valve shown in Fig. 1;

Fig. 5 is a right side view of the seal for flow control valve shown in Fig. 1, the left side view being a mirror image thereof;

Fig. 6 is a cross-sectional view of the seal for flow control valve shown in Fig. 1, where the view is sectioned vertically at the center of the right side view shown in Fig. 5;

Fig. 7 is a cross-sectional view of the seal for flow control valve shown in Fig. 1, where the view is sectioned vertically at the center of the front view shown in Fig. 4;

Fig. 8 is an enlarged portion of the cross-sectional view shown in Fig. 6; and

Fig. 9 is a cross-sectional view showing the seal for control valve in one contemplated state of use.

(Continued)

Throughout Figs. 1-9, the broken lines denote aspects of the seal for flow control valve that form no part of the claimed design.
